UNITED STATES PATENT OFFICE

102,434

DESIGN FOR A HINGE FOR SCREEN DOORS OR THE LIKE

Onnie Mankki, Cleveland Heights, Ohio, assignor to The Champion Hardware Company, Geneva, Ohio, a corporation of Ohio

Application August 21, 1936, Serial No. 64,507

Term of patent 7 years

To all whom it may concern:

Be it known that I, Onnie Mankki, a citizen of the United States, residing at Cleveland Heights, in the county of Cuyahoga and State of Ohio, have invented a new, original, and ornamental Design for a Hinge for Screen Doors or the like, of which the following is a specification, reference being had to the accompanying drawing, forming a part thereof, in which:

Fig. 1 is a face view of the hinge showing my new design, and

Fig. 2 is a top plan view.

I claim:

The ornamental design for a hinge for screen doors or the like substantially as shown.

ONNIE MANKKI.
